United States Patent Office.

ISRAEL KINNEY, OF WOODSTOCK, CANADA.

Letters Patent No. 93,825, dated August 17, 1869; patented in Canada, April 5, 1867.

IMPROVEMENT IN CARRIAGE-SEAT.

The Schedule referred to in these Letters Patent and making part of the same.

Be it known that I, ISRAEL KINNEY, of Woodstock, Canada, have invented a certain new and useful Improvement in Buggy-Seat; and I do hereby declare that the following is a full and exact description thereof, reference being had to the accompanying drawings, making part of this specification.

In the specifications above referred to—

Figure 1, on the accompanying drawings, represents a perspective view of the seat, with lazy-back, suitable for adjusting a top to the same.

Figure 2 shows an elevation of the same.

Figure 3 shows a plain inside view, with lazy-back and top removed.

Figure 4 represents an outside view of one side of the seat.

Figure 5 represents an inside view of one side of the seat.

Figure 6 represents an inside view of the back part of the seat.

For a particular description of the seat, refer to the plan, fig. 3, and the letters thereon marked.

Letters G show the back and sides of the seat, which are composed of metal, and may be either cast or bent into any desired form or shape.

Letters E represent a flange, forming part of the

same, to which is attached a wooden bottom, by means of screws or nails through the small holes represented on the flange.

Letters F show the ears or lugs, by means of which to attach a lazy-back or top, or both combined, and any number of those ears or lugs which may be desired can be put on, or the seat can be made without any, if desired, and the top and lazy-back can be made either fixed or movable.

Letter H, on fig. 4, represents a curtain, which extends around the outside of the seat, at the bottom, which is also made of metal, and cast or bent into the desired form, and can be either made in one piece with the seat, or separate, as desired.

What I claim as my invention, is—

In the first place, making the sides and back of the seat of one piece of cast-metal; second, making the curtain in the same manner and of the same materials as the sides and back, this curtain being in one piece with the seat, or not, as desired.

ISRAEL KINNEY.
